(57) **CLAIM**

We claim the ornamental design for a can holder, as shown and described.

DESCRIPTION

FIG. 1 is a perspective view of a can holder showing our new design;

FIG. 2 is a front view thereof;

FIG. 3 is a back view thereof;

FIG. 4 is a left-side view thereof;

FIG. 5 is a right-side view thereof;

FIG. 6 is a top view thereof;

FIG. 7 is a bottom view thereof; and,

FIG. 8 is a perspective view of the can holder shown in an environment of use.

The broken lines in FIG. 8 depict environment and form no part of the claimed design.

1 Claim, 6 Drawing Sheets
